United States Patent Office

Des. 200,995
Patented Apr. 27, 1965

200,995

WATER CONDITIONER

James E. Hiers, Ramsey County, and Leo F. Wildgen,
Hennepin County, Minn., assignors to Union Tank Car
Company, a corporation of New Jersey

Continuation of design applications Ser. No. 77,689 and
Ser. No. 77,690, Dec. 6, 1963. This application Nov.
27, 1964, Ser. No. 82,809

Term of patent 14 years

(Cl. D91—1)

FIGURE 1 is a front perspective view of one embodiment of a water conditioner showing our new design, FIGURE 2 is a top plan view of the embodiment of FIG. 1,

FIGURE 3 is a fragmentary side elevational view of the embodiment of FIG. 1,

FIGURE 4 is a front perspective view of another embodiment of a water conditioner showing our new design,

FIGURE 5 is a top plan view of the embodiment of FIG. 4, and

FIGURE 6 is a fragmentary side elevational view of the embodiment of FIG. 4.

The dominant features of our design reside in the portions shown in full lines.

This application is a continuation of our copending applications Serial Numbers 77,689 and 77,690, filed December 6, 1963, now abandoned.

We claim:

The ornamental design for water conditioner, as shown and described.
